UNITED STATES PATENT OFFICE.

WILLIAM B. SHAW, OF BROOKLYN, NEW YORK.

DESIGN FOR A TIP FOR SHADE-ROLLERS.

SPECIFICATION forming part of Design No. 26,561, dated January 26, 1897.

Application filed November 23, 1896. Serial No. 613,229. Term of patent 14 years.

To all whom it may concern:

Be it known that I, WILLIAM B. SHAW, a citizen of the United States, residing at Brooklyn, in the county of Kings and State of New York, have invented and produced a new and original Design for a Tip for Shade-Rollers, of which the following is a specification, reference being had to the accompanying drawings, forming a part thereof, in which—

Figure 1 is a perspective view of a shade-roller tip embodying the features of my design, and Fig. 2 is a transverse section through the said tip.

The design consists in the longitudinal de-

pression of the tip to form a longitudinal exterior channel A, which channel has two inwardly-extending parallel side walls and a base-wall connecting the said walls and the annular bead B at one end of the tip, and having a notch b coincident with the channel. 15 20

I claim—

The design for a shade-roller tip, substantially as herein shown and described.

WILLIAM B. SHAW.
